United States Patent Office.

LEWIS T. CLEMENT, OF SMYRNA, TENNESSEE.

Letters Patent No. 93,057, dated July 27, 1869.

IMPROVEMENT IN MACHINE FOR GINNING AND CLEANING COTTON.

The Schedule referred to in these Letters Patent and making part of the same.

To all whom it may concern:

Be it known that I, LEWIS T. CLEMENT, of Smyrna, in the county of Rutherford, and State of Tennessee, have invented a new and improved "Machine for Ginning and Carding Cotton;" and I do hereby declare that the following is a full, clear, and exact description of the same, reference being had to the accompanying drawings, which form part of this specification, and in which—

Figure 1 represents a longitudinal section of a machine for this purpose, constructed according to my invention, and

Figure 2, a plan view of the same.

Figure 3 is an enlarged view of the device for operating the reciprocating brush.

Similar letters of reference indicate corresponding parts in both figures.

This invention has for its principal object the production of a continuous bat, or sliver of cotton fibre, and also of a cleaner and better quality of lint direct from seed-cotton; and, to this end,

It consists of a cotton-ginning and carding-machine, of novel construction, whereby the desired objects are attained.

Referring to the accompanying drawings—

A represents the main card, and

B, the doffer-wheel of an ordinary carding-machine.

C is a cylindrical shaft, upon which is carried the usual series of circular saws c.

Between the card A and saw-shaft C is arranged a revolving cylinder, or drum, D, upon the periphery of which is carried a continuous brush, which covers its entire periphery, and which is designed, by means of its continuous nature, to convey the lint from the teeth of the saws to the card-wheel A, in a continuous unbroken sliver.

This drum D is provided not only with a rotary, but also with a longitudinal reciprocating motion, for the purpose of distributing the lint more evenly and uniformly upon the card.

This reciprocating motion may be imparted to said rotating brush, by means of a cam-disk, d, set at a suitable angle on the shaft of the brush, and working in a fixed guide, b, attached to the frame of the machine, as shown in fig. 3.

E is a shaft, arranged a little above the separating line of the saw-shaft C and the brush D, and parallel therewith.

Said shaft E is armed with any number of radial beating, or combing-plates, f, which are supplied, at their outer edges, with slots or notches, corresponding in number with the number of circular saws upon the saw-shaft.

Through these said slots the teeth of the said saws are made to pass, while, by the revolving of the said beating, or combing-plates f, in an opposite direction, the slots of each plate are carried, in rapid succession, astride the said teeth, in such manner as to exert a beating, or combing action upon the lint, thereby separating the motes and other foreign matter from the same, while it is being carried upon the saws.

By this means, the said lint may be left comparatively free from motes and other extraneous matter.

The manner of operating the machine is substantially the same as that of other machines of similar character.

What is here claimed, and desired to be secured by Letters Patent, is—

1. The rotary brush D, having a continuous surface, in combination with the saws C and carding-cylinder A, substantially as and for the purpose herein described.

2. The combination, with the above, of the cam-disk d, operating in a fixed guide, secured to the frame, for communicating a reciprocating motion to the rotary brush D, as set forth.

3. The combination, with the saws, of a cotton-ginning machine, of revolving, beating, or combing-plates f, having slotted outer edges, whereby motes and other extraneous matter may be separated from the lint, while it is being carried upon the saws, substantially as herein described.

4. The rotary brush D, having a reciprocating motion in direction of its axis, substantially as and for the purpose set forth

LEWIS T. CLEMENT.
